MEANS FOR CONTROLLING WILDNESS OF
YARN DURING DELIVERYHenry M. Strub, Jr., Charlotte, N.C., assignor to The
Duplan Corporation, New York, N.Y., a corporation
of New York

Application August 21, 1956, Serial No. 605,359

9 Claims. (Cl. 66—125)

The present invention relates generally to controlling the inherent wildness of lively or stretch yarns as the yarn is taken from the supply package and passes to any form of web forming machine, such as a knitting machine or to any conventional winding, twisting or quilling machine.

Several difficulties arise when unwinding a lively or stretch yarn from yarn supply packages or cones due to the inherent characteristic of this yarn to twist and curl upon itself when in a relaxed state or at any time that a slight tension is not placed on this yarn. It is also quite difficult to control and provide a uniform tension on the yarn as it is taken off the supply package since the yarn is wound onto these supply packages so that, as the yarn is removed, the loop unwound from near the top of the supply package will ordinarily require less tension than the loop unwound from near the bottom of the package. In cases, such as a knitting machine, where the yarn is drawn from packages in intermittent steps, these lively or stretch yarns have a tendency to curl up and twist upon themselves the moment the yarn ceases its travel from the yarn supply package.

It is a primary object of this invention to provide a resilient device to surround the yarn supply package and to contact the outer periphery thereof by placing a very slight tension on the yarn being unwound and, to thus prevent the yarn from curling and kinking upon itself due to the twist in the yarn or the crimp therein.

It is another object of this invention to provide a holder for the resilient device which may be adjusted to the particular size yarn supply package being used so as to vary the tension on the yarn as it is removed from the outer periphery of the yarn supply package.

Some of the objects of the invention having been stated, other objects will appear as the description proceeds, when taken in connection with the accompanying drawings, in which—

Figure 1 is an isometric view of one form of the resilient tension and yarn control device removed from the supporting bracket;

Figure 2 is a side elevation of this form of resilient tension device supported by a first form of holder;

Figure 3 is another view of this same holder turned 45 degrees and showing the resilient tension device in a different position on the holder;

Figure 4 is a side elevation of a second modified form of holder;

Figure 5 is a plan view of the holder, yarn supply package and resilient tension device shown in Figure 4;

Figure 6 is an isometric view of a second modified form of resilient tension device;

Figure 7 is an isometric view of a third modified form of holder for the tension device shown in Figure 6;

Figure 8 is an exploded isometric view of another type of yarn supply package and stand therefor adaptable to receive the holder and tension device shown in Figure 7;

Figure 9 is a side elevation of the yarn control device,

2

the holder, stand and yarn supply package in assembled or operative position.

Referring more specifically to the drawings, it will be noted that the first form of yarn control device of the present invention, shown in Figures 1 through 5, is particularly adaptable for use with a package of the cone type and is shown in connection with a tapered cone. It is to be understood that this device is not to be limited to use with a tapered cone as it will work equally as well with a straight sided cone. The form of the improved yarn control device shown in Figures 6 through 9 is particularly adaptable for use with a yarn supply package which has flanged ends thereon and it is to be understood that this form of the invention may also be used with the cone type packages as well.

Figure 1 shows one form of resilient member in the form of a tube 10 which is shown and described as a tube knit from any of the stretch yarns. The tube 10 may be knit from a non-stretch yarn with an elastic yarn incorporated therein or may be braided, woven, or molded from a resilient material such as rubber as long as the stretch or resilient quality is retained. As one example, but a nonlimiting example, of a method of producing this resilient tubular member is to knit two ends of 30 denier plied right and left twist Helanca yarn on a circular 108 needle 4 inch knitting machine to the proper length, which in this case is approximately 3 inches in the relaxed or contracted condition.

One form of holder or support for this resilient tube 10 is shown in Figures 2 and 3 and comprises a base or stand 11 with an opening 12 cut therein for insertion of the lower end of a cone 13 which has a yarn 14 wound thereon to form what is generally known as a package 14a. A plurality of upstanding legs or supports 16 are provided the lower ends of which penetrate the stand 11 and the lower inturned portions of which are fixed to the lower edge of the base 11. Each of the support members 16 are provided with a pair of adjustable upper and lower set collars, the upper collars indicated at 20 and the lower collars indicated at 21. The collars 20 and 21 each have locking screws 22 inserted therein adapted to engage the support rods 16 to lock the collars 20 and 21 in the desired vertical location on the supports 16.

The lower edge of the tubular member 10 is stretched and diametrically opposed points are placed on the four supports 16. The collars 21 are then placed on the supports 16, and the collars 20 spaced the desired distance above the collars 21 and diametrically opposed points of the upper edge of the tube 10 are then placed on the supports 16. By varying the vertical distance between the upper collars 20 and the lower collars 21, the amount of tension placed on the outer periphery of the yarn package 14a and the area of the package contacted by the tube 10 may be varied to adjust the amount of drag on the yarn so that light even drag or tension will be maintained, as it is pulled off or unwound from the package 14a by any suitable yarn take-up mechanism, such as a knitting machine, winding or twisting machine indicated at 25 in Figure 3. As the collars 20, 21 are moved closer together (Figure 2) the amount of tension with which the resilient tube 10 grips the yarn package 14a increases and as the collars 20, 21 are moved a greater distance apart, along the supports 16, (Figure 3) the gripping tension around the package 14a decreases. The point at

which the tube 10 contacts the package 14a may also be moved vertically by movement of the collars 20, 21. It has been found that the best results are obtained when the point at which the tubular member 10 contacts the yarn package is approximately one to one and a half inches from the top of the yarn package 14a, but the

device will apply a light tension to the package if contact is made at any point along the vertical height of the yarn package 14a.

The modified form of tubular holder shown in Figures 4 and 5 comprises a base 30 and four upstanding tubular support members 31, the lower ends of which are turned inwardly and fixed on the bottom of the base member 30 and the upper ends are provided with crimped or saw-tooth portions 32 for reception of the upper and lower edges of the resilient tubular member 10. The crimped portions 32 take the place of the collars 20, 21 and provide a means for adjusting the distance between the upper and lower edges of the tube 10. As heretofore pointed out, the distance between opposite ends of the tubular member 10 determines the amount of tension placed on the yarn 14 as it is taken off the package by the yarn take-up 25.

The modified form of the resilient tubular member, shown in Figure 6 and indicated at 40, may be knit on the same type knitting machine and in the same manner as the resilient tube 10, shown in Figure 1, the only difference being in the length thereof. The type of holder provided to support this tubular member 40 (Figures 7, 8 and 9) comprises a base bobbin support 41 provided with an opening 42 therein for the reception of the spindle 43 of a bobbin 44 of the type which is usually provided with respective lower and upper flanges or head members 45 and 46. This bobbin 44 is the type usually used as the take-up bobbin on winding or twisting machines and is sometimes used as a supply package for knitting machines. A yarn 47 is wound on the bobbin 44 to form a yarn package 48. A tubular holder 50, which may be made from paper, metal or any form of plastic material, is provided to support and stretch the opposite ends of the tubular member 40. The top and bottom of the tube 40 are stretched over the upper and lower edges of the holder 50 and secured thereto by any suitable means such as adhesive tapes or bands 49. The lower edge of the holder 50 with the tubular member 40 secured thereto is then placed on and supported by the base 41 so that a portion of the tubular member 40 will engage the package 48 and the upper flange 46 of the bobbin 44 (Figure 9). Thus, the tube 40 maintains a light even gripping tension on the yarn package 48 and on the outer edge of flange 46 as the yarn 47 is withdrawn by any suitable yarn take-up 51. Thus, the yarn 47 being removed from the package 48 is constantly under a very light tension to prevent unnecessarily unlooping or unwinding as the yarn take-up 51 pulls the yarn 47 from the package 48. The tube 40 also causes the yarn 47 to ride around and against the head member 46 as it is removed by the yarn take-up 51 and prevent ballooning of the yarn. In some cases, a smooth tight fitting cap, not shown, may be placed over the head member 46 of the bobbin 44 to protect the yarn 47 from engaging any rough spots or nicks in the edge of the head member 46 as it is unwound.

It is thus seen that there has been provided a yarn control device in the form of a tubular resilient member adapted to surround and lightly engage the yarn supply package to apply an even, constant tension to the yarn as it is pulled from the yarn supply package to any suitable yarn take-up mechanism.

In the drawings and specification there has been set forth a preferred embodiment of the invention, and although specific terms are employed they are used in a generic and descriptive sense only and not for purposes of limitation, the scope of the invention being defined in the claims.

I claim:

1. An apparatus for controlling a lively yarn as it is withdrawn over one end of a yarn supply package comprising a resilient tubular member surrounding said yarn supply package, said tubular member being stretchable

lengthwise and widthwise, and a support for said resilient tubular member for expanding opposite ends of said tubular member substantially equal amounts to hold the central portion only of said tubular member in resilient engagement with a circumferential area of said yarn supply package adjacent the end over which the yarn is withdrawn.

2. In an apparatus for controlling a lively yarn as it is withdrawn over one end of a yarn supply package comprising the combination of a tubular resilient member having open opposite ends and stretchable lengthwise as well as widthwise, and a support for holding said resilient tubular member having a base and means for stretching opposite ends of said tubular resilient member supported by said base, said support surrounding said yarn supply package and supporting said tubular resilient member so that the central portion of said tubular member engages a circumferential area adjacent the delivery end of said yarn supply package.

3. A device for controlling a lively yarn as it is removed from one end of a yarn supply package comprising a tubular resilient member surrounding said yarn supply package, said tubular member being stretched widthwise substantially equal amounts at opposite ends with the medial portion only engaging a circumferential area of said yarn supply package adjacent the yarn take-off end only, and a support member to which the opposite ends of the tubular resilient member are secured.

4. In a device according to claim 3 wherein said support member comprises a base, upstanding legs on said base adapted to receive the stretched opposite ends of said tubular member and means on said legs for adjusting the distance between opposite ends of said tubular member.

5. In a device according to claim 4 wherein said adjustment means on said legs comprises adjustable set collars engageable with opposite ends of said tubular member.

6. In a device according to claim 4 wherein said adjustment means on said legs comprises crimped portions engageable by opposite ends of said tubular member.

7. A device for controlling a lively yarn as it is removed from one end of a yarn supply package comprising a tubular resilient member, said tubular resilient member being stretched at opposite ends with the central portion thereof surrounding and engaging a circumferential area adjacent the yarn takeoff end only of said yarn supply package, and a rigid tubular support member surrounding said tubular resilient member and to which the opposite stretched ends of the tubular resilient member are secured.

8. An apparatus for controlling a lively yarn as it is unwound from one end of a yarn supply package comprising a tubular resilient member surrounding said yarn supply package, said tubular member being expanded at opposite ends substantially equal amounts and to a diameter substantially greater than the diameter of the yarn supply package with the medial portion thereof engaging a portion only of said yarn supply package,

60 a rigid tubular support member surrounding said tubular resilient member and to which the opposite expanded ends of the tubular member are secured, and a base member supporting said yarn supply package and said rigid tubular member whereby the medial portion of said tubular resilient member engages the yarn takeoff end only of said yarn supply package.

9. A device for controlling a lively yarn as it is removed from one end of a yarn supply package comprising a tubular resilient member surrounding said yarn supply package, said tubular member being stretched substantially equal amounts at opposite ends, the unstretched central portion of said tubular resilient member engaging a circumferential area of said yarn supply package adjacent the yarn takeoff end only, the area of

engagement of said tubular resilient member extending in a direction lengthwise of said yarn supply package less than one half the length of the package, and a support member to which the stretched opposite ends of the tubular resilient member are secured.
